Primary Examiner — Deanna L Pratt*Assistant Examiner* — Natasha Vujcic*(74) Attorney, Agent, or Firm* — Manabu Kanesaka(57) **CLAIM**

The ornamental design for a hole plug, as shown and described.

DESCRIPTION

FIG. 1 is a perspective view from the plan side of a hole plug showing my new design;

FIG. 2 is a perspective view from the bottom side thereof;

FIG. 3 is a plan view thereof;

FIG. 4 is a bottom view thereof;

FIG. 5 is a front view thereof; a rear view being symmetrical to the front view;

FIG. 6 is a right side view thereof;

FIG. 7 is a left side view thereof;

FIG. 8 is a cross-sectional view thereof along the line 8-8 in FIG. 3;

FIG. 9 is a cross-sectional view thereof along the line 9-9 in FIG. 3;

FIG. 10 is a perspective view from the plan side of another hole plug showing my new design;

FIG. 11 is a perspective view from the bottom side thereof;

FIG. 12 is a plan view thereof;

FIG. 13 is a bottom view thereof;

FIG. 14 is a front view thereof; a rear view being symmetrical to the front view;

FIG. 15 is a right side view thereof;

FIG. 16 is a left side view thereof; and,

FIG. 17 is a cross-sectional view thereof along the line 17-17 in FIG. 12.
